BOTTLE

Albert Fine, Baltimore, Md., assignor to High Rock Ginger Ale Company of Baltimore city, a firm composed of Harry B. Gorfine and Julius Novey, trustees, and Albert Fine, copartners

Application December 1, 1952, Serial No. 22,512

Term of patent 14 years

(Cl. D58—9)

To all whom it may concern:

Be it known that I, Albert Fine, a citizen of the United States, residing at Baltimore city, State of Maryland, have invented a new, original, and ornamental Design for a Bottle, of which the following is a specification, reference being had to the accompanying drawing, forming a part thereof, in which:

The dominant feature of my design resides in the portions shown in full lines.

I claim:

The ornamental design for a bottle, as shown and described.
